METHOD OF AND APPARATUS FOR ISOLATING MINERALS

Henry L. Alexander, Wilmington, and Hubert I. du Pont, Rockland, Del., and Willing B. Foulke, Media, Pa., assignors to E. I. du Pont de Nemours & Company, Wilmington, Del., a corporation of Delaware

Application August 31, 1936, Serial No. 98,819

10 Claims. (Cl. 269—172)

This invention relates to the separation of minerals from gangue by the use of a liquid of specific gravity between that of the mineral and the gangue. The invention will be described as it is applied to the separation of coal from its indigenous impurities, particularly slate, a separation in which the process and apparatus are of particularly great value, but it is to be understood that this description is illustrative, not limitative.

Coal appears to have been known, and to some small extent used by, the ancients. Its use in China at about the year 1200 is described by Marco Polo and about 1500 Agricola described a process of freeing minerals from their gangue which is the direct progenitor of the jig process of coal cleaning, which has the widest use today. In the early days of coal mining in Europe and in the United States only the thick seams were mined. Hand methods were largely in vogue and the need for anything except hand cleaning, or the most crude of mechanical methods was unnecessary. As the thick seams were used up, however, it became necessary to use thin seams and seams containing veins of rock, which entailed the necessity of removing the rock before the coal could be sold. The method which came most prominently into use and which is today the standard of separating coal and slate depends upon the rates at which bodies of different densities sink through a liquid such as water. It is known that bodies sink through a liquid at rates which are functions of their respective densities, the denser sink the more swiftly. The standard jig washer of the industry takes advantage of this principle, but instead of permitting the solids to sink through the liquid, the liquid is forced through a screen on which the solids rest at a rate which lifts the layer of coal off the heavier slate, the coal being carried with the rush of liquid over a weir and the slate being discharged at a lower point from the screen. Jigs are highly developed and are of excellent capacity and performance. However, the competition of oil has driven coal producers to find means of cleaning coal which will be more accurate in separating useful from useless lumps and producers and inventors have turned their thoughts to those processes of separation which depend upon the parting action of a liquid having specific gravity between that of coal and that of slate.

The use of a parting liquid is to be distinguished from froth flotation. Froth flotation alters the apparent specific gravity of a body by

encasing it within a bubble. Parting processes, however, depend upon the use of a parting liquid in which one ingredient of the mixture will sink down and another ingredient of the mixture will rise to and float on the top. Certain phases of the parting liquid process are affected by the phenomenon of altered specific gravity but they are distinguished from froth flotation.

The suggestion was made toward the middle of the nineteenth century that ferric chloride or sulfuric acid could be used as a parting liquid for the separation of coal and slate and attempts were made in England to run the ferric chloride process in competition with the jigs, but the jigs were highly developed, the use of a parting liquid was a bare suggestion and the attempt was a failure because of the undeveloped state of the new process, the highly developed state of jig separation, and the inability of experimenters to make the parting process a success in itself. The original attempt having been made, however, subsequent inventors worked with the suggested process and a host of patents have been issued, particularly in England and in the United States, dealing with processes of the parting liquid type. To the best of our knowledge and belief, however, the only such process that has been used successfully is one that depends upon the parting effect of a suspension of solids such as sand or clay in water. The art with respect to parting media of homogeneous character is in the industry today as it was in the nineteenth century, unable to compete. The parting liquids are worth more than the coal and the losses thereof are so great that they outweigh the theoretical advantages of more accurate separation. The processes themselves, being crude and undeveloped, are incapable of competing with the highly developed processes already in use in the industry. They are incomplete processes, lacking a number of elements essential to success.

It is an object of this invention to separate coal from slate, and other minerals from their gangues or from each other, by a process which depends upon the parting effect of a liquid of intermediate specific gravity. Another object of the invention is to present an apparatus so highly developed that it may compete successfully with the highly developed processes and apparatus of the prior art. Another object of the invention is to bring into the mineral separations art new methods and apparatus for separating minerals from their gangues.

The objects of the invention are accomplished, generally speaking, by immersing the mixed min-

erals and gangue, preferably under hermetical seal, in a parting liquid of specific gravity intermediate, the specific gravities of materials to be separated, withdrawing the separated constituents from the parting liquid, scrubbing them to remove adhering parting liquid, preferably under hermetical seal, and ejecting them, preferably through a hermetical seal, from the process, and recovering parting liquid from the scrubbing liquid in a semi-static settling system.

The objects of the invention are also accomplished in part by the association of apparatus hereinafter more fully described. The objects of the invention are in some degree accomplished by the details of the apparatus and process which are more completely elsewhere herein described.

In order to make the drawings more easily comprehensible the first figure has been called Figure 1, and is the key figure; the steps of the process have been numbered from 3 to 9 consecutively and the figures of the drawings have been numbered to correspond with the steps of the process to which they refer. For example, on the key figure (Figure 1) the numeral 3 refers to the step of the process which involves the actual parting step. The sheets which relate to that step are numbered from Figure 3 to Figure 37. Figure 2 is a view of the pipe joints which are used throughout the apparatus.

Figure 3 is an apparatus capable of carrying out the parting step of the process; Figure 3 is a vertical section on the line A—A of the key figure; Figure 3a is a cross-section on the broken line 3a, 3a of Figure 3; Figure 3b is a detail, partly in section, of a preferred modification of wedge 336—337; Figure 3c is a section on Figure 3b; Figure 3d is an elevational view partly in phantom and partly in section showing the parting apparatus; Figure 3e is a section of line 3e, 3e of Figure 3d; Figure 3f is a section of line 3f, 3f of Figure 3d; Figure 3g is a section on line 3g, 3g of Figure 3; Figure 3h is a section on line 3h, 3h of Figure 3; Figure 3i is a section on line 3i, 3i of Figure 3; Figure 3j shows means for operating the preferred embodiment of Figures 3b and 3c; Figures 3k and 3l show a preferred method of operating the apparatus of Figures 3b and 3c.

Figure 4 is an elevational view partly broken away and in section showing the scrubbing apparatus; Figure 4a is a section on the line 4a, 4a of Figure 4; Figure 4b is an enlarged section on the line 4b, 4b of Figure 4d, the left hand section of Figure 4b taken on the line Z—Z of Figure 4d; the middle section of Figure 4b being taken on the line Y—Y of Figure 4d; and the right hand section of Figure 4b being taken on the line X—X of Figure 4d; Figure 4c is a section on the line 4c, 4c of Figure 4; Figure 4d is an enlarged section of the sealing mechanism shown in Figure 4c; Figure 4e is an enlarged section of a spray pipe with nozzles showing the overlap of the sprays.

Figure 5 discloses the apparatus for receiving material discharged from the scrubbing process, for sealing the scrubbing process, and for discharging the material.

Figures 6, 6a, 6b, and 6c disclose the second, or main, settling tank, being the second step in the heavy liquid recovery system of which the first step is the settling tank, the apparatus which is found within the scrubbing section. Figure 6 is a plan view partly cut away and in section of the main settling tank; Figure 6a is a section on

the line 6a, 6a; Figure 6b is a vertical section on the line 6b, 6b; Figure 6c is an enlarged section on the line 6c, 6c of Figure 6.

Figures 7 to 7c refer to the third settling tank of the series, so-called the sludge trap, and to the still. Figure 7 is an elevation partly in section of the sludge trap and still as assembled; Figure 7a is a plan view of the sludge trap; Figure 7b is a cross-section of the sludge trap on line 7b, 7b; Figure 7c is a plan view of the still on the line 7c, 7c of Figure 7.

Figures 8 to 8c do not refer to section 8 of the apparatus, but to an apparatus by means of which the efficiency of separation can be expeditiously determined. Figure 8 is an elevation of a portion of the apparatus partly in section and Figure 8a is a cross-section on the line 8—2, 8—2 of Figure 8. Figure 8b is a drawing of a scoop; Figure 8c is an enlarged detail of the hinge connection.

Figure 9 and Figure 9a are views in plan and elevation, respectively, of the condensers.

In order to simplify the comprehension of the invention the path of the coal through the apparatus will be traced to completion before the treatment of used liquids is considered. The coal is dropped into chute 328 and is carried thereby into the separating chamber where the heavy material is separated from the light by a liquid medium of intermediate specific gravity. After the separation the coal is drained of entrained liquid and transferred to the apparatus and step 4 of the process which is, with respect to the coal, a scrubbing process which removes from the coal substantially all vestiges of parting liquid. In this scrubbing step the separated coal and slate are subjected to a vigorous scrubbing by water, under pressure, which comes from headers 442. The steps of the process are preferably carried out in a hermetically sealed system. The washed coal and slate are ejected through split boot 462 into the water-sealed conveyors 5 which serve to give the coal a last rinsing and to prevent the escape of vapors from the sealed units 3 and 4. From the conveyors 5 the coal may be discharged to storage or to a railroad car for transportation to the place of use and the slate may be discarded.

When the coal passes through the scrubbing section 4, it is vigorously scrubbed with water from the headers 442. The coal passes on and the water passes through the screen which carried the coal and, together with sludge and heavy liquid, gathers in tank 406 which forms the lower part of this section of the apparatus. From that tank the sludge is removed through pipe 451 to be discharged into the sludge trap 7, and the liquid containing lighter suspended matter is discharged into the main settling tank 6. Over the weir at the top of the main settling tank 6 flows comparatively clear liquid to be pumped through pipe 615 to headers 442 for reuse in the washing section. From the bottom of the tank 6 the sludge is drawn through pipe 620 and pumped to the sludge trap 7. From the sludge trap 7 on some occasions substantially the entire contents are dropped into the still 8 for steam distillation, but in normal and preferred operation the matter is allowed to settle into three layers, the bottom of which is largely solid, the middle of which is largely heavy liquid and the upper of which is substantially water. Through the pipe 717 which leads to a weir at the top of the tank and through valves 719 and pipe 721 the water is drawn off and returned to the tank 6.

The heavy liquid is pumped through pipe 123 to the used liquid storage tank. Finally, the remaining sludge is dropped into the still 8 for steam distillation. The water, together with vaporized heavy liquid, passes through pipe 88-89 to condenser 9 which is diagrammatically shown on this figure, and from condenser 9 to cooler 95 and water separator 96, wherein the heavy liquid is separated by a gravity separation from water. The separated heavy liquid is carried through pipes 961 and 962 to the new liquid storage tank 963 or the used liquid storage tank 964, respectively. 965 is a vent pipe connecting the used liquid storage tank with the new liquid storage tank and 966 is a vent from the new liquid storage tank. The used liquid storage tank can be replenished from the new liquid storage tank through meter gauge 967, which gives a check on the amount of liquid used in the system. The level of heavy liquid in the parting section 3 is maintained by injecting liquid from the used storage tank 964 through pipe 359. Excess of heavy liquid escapes over a weir through pipe 358 and back to the used liquid storage tank. In the drawings a circle with the letter *p* indicates a pump and a circle with the letter *x* indicates a valve; pipes 358-359 are joined by a pipe in which is valve V-20.

In Figures 3 to 31 is illustrated the separating chamber. Referring to the numerals, 3 is an enclosed tank; 31 are channel-shaped edges to openings in the top of the tank; 32 are covers for the said openings; 33 are flanges on the said covers of size to fit within the said channel-shaped edges of the openings; 34 is a liquid which partially fills each said channel-shaped opening forming a hermetical seal; 35 is a vent pipe; 37 is a motor support mounted on the said tank; 38 is a motor of variable speed; 39 is a speed reducing gear of customary construction comprising a chain of large and small driving and driven wheels; 300 is a shaft running crosswise of and projecting somewhat beyond the sides of the tank; 301 and 302 are sprocket wheels keyed to the shaft 300 at opposite ends thereof; 303-304 are chains on opposite sides of the tank driven from the said sprocket wheels respectively; 305-306 are sprocket wheels mounted on the ends of shafts 307 and 308 respectively, said shafts passing through the wall of the said tank; 309-309 are stuffing boxes which can be filled with grease from the outside of the tank through the fittings 310; 312 are sprocket wheels keyed to the shaft 308; 313 are wheels mounted on shafts 314 which are journaled within the tank; 315 is a wedge-operated take-up mechanism whereby one roller 313 can be moved longitudinally of the machine to take up the slack in the chain. One take-up means is placed at each end of the roller. 316 is a screw for operating the wedge and moving the roller; 317-317 are conveyor chains; 318 is a flight of a conveyor which is mounted on the conveyor chains 317; 319 are perforations in the flights of the conveyor; 320 is a conveyor pan bent at the point 321 and having a discharge lip and chute 322; 323 is a wedge-wire screen forming the bottom of the upper portion of the conveyor pan; 324 is a section of the tank wall spaced considerably away from the said screen to permit liquid to make its way through the said screen and to be collected in the said portion of the tank; 325 is a channel leading from the portion 324 past the outside of the tank and connecting with the interior of the tank at 326; 327 are blow-out connections to permit the forcing of a stream of

water or other liquid into the tank at that point; 328 is a chute projecting through the side of the tank; 329 are dividing walls in the chute; 330 is the back plate of a hopper; 331 are perforations in the back part of the hopper; 332 is a portion of the hopper back plate which is inclined diagonally forward and which contains the perforations 331; 3320-3320 are perforated portions of the said back plate of the hopper which are continued beyond the side plates thereof; 333-334 are side walls of the said hopper, both being inclined inwardly to the degree necessary to constrain any material entering through the chute 328 and passing to the bottom of the tank to fall within the conveyor pan; 335 is the front wall of the said chute which is constructed, in the form of the invention shown in Figure 3, as one piece of the front conveyor pan; 336 is a section of the said wall inclined diagonally toward the receiving end, and 337 is a portion of the said wall inclined toward the discharge end whereby to present the wedge face toward the charging end; 338 is a conveyor pan; 339 is a wedge-wire screen forming the bottom of the upper portion thereof; 340 is a discharge chute attached to or forming a part of the said conveyor pan; 341-341 are sprocket wheels on the shaft 307 over which are trained the chains 342-342 of a flight conveyor 343; 344 is a bend in the said flight conveyor pan; 345 is a shaft carrying two sprocket wheels at the said bend; 346 is an extension of the conveyor pan beyond the sprocket wheels 345 and being continued downwardly to form the wedge; 347 are means for adjusting the position of the sprocket wheels 348 which are mounted on a trunnion to carry scraper flight conveyor 343; 349 is a pan extending from side to side of the machine to catch the drip which passes through the wedge-wire screen 339 and return it to the liquid in the tank; 350 is a drain at the rear and lowest point of the tank, whose bottom is preferably inclined; 351 is a chamber beneath the said screen; 352 are a pipe and valve to permit the drawing off of the sludge which may collect and pass through the said screen, the said sludge being passed through the said pipe to the settling tank to be hereinafter described, the continuation of the said pipe not being shown; 353 is a chamber attached to the wall of the tank; 354 is a screw operating in a nut 355 fastened to the tank; 356 is a stuffing box through which the said screw passes; 357 is a cylinder attached to the said screw; 358 is a pipe projecting within the box 353 and within the cylinder 357 having therewith a movable fit made liquid-tight by machining or by the use of a satisfactory sealing material; 359 is a valved pipe leading to the box 353; 360 are openings below the parting liquid level connecting tank 3 and weir box 353; 3601 is an opening connecting weir box and tank above the water level; 361 is an enclosed weir box on the side of the machine; 362 is a pipe weir within the box to control the water level. The pipe 362 is connected to the settling tank. 363 is a pipe leading at 364 and 365 into the tank; 366 is a hollow gauge within the pipe 363 and projecting thereabove. Shaft 366 of the said gauge is preferably calibrated on its outside and its hollowness is used for the insertion or withdrawal of shot or other heavy material to its interior so that it can be standardized against the specific gravity of the parting liquid in the apparatus to record correctly its level; 367-368 are oppositely placed hollow projections on the sides of the apparatus; 369-370 are removable covers held on by bolts or other

satisfactory means not shown to hermetically seal those of the said openings which are not in use; 371—371 are flanges on the said projections designed to abut against and form a hermetical seal with similarly placed flanges or similarly projecting members of that apparatus 4 which accomplishes the next step in the process; 3280 is a manifold forming a part of the chute connected to a suction apparatus not shown and through openings 3281 to the chute whereby any escaping gases may be caught; 372 indicates the framework which supports the tank; the line 373 indicates the upper level of the liquids in the tank; the line 374 indicates the interface of the separating liquid and the light liquid; 375 is a pipe opening into the tank whose purpose will be hereinafter described; 377—377 are angle bars supported either from the members 332 and 337 or from the sides of the tank by bars which cover the conveyor chains and prevent them from being damaged by the descending slate; 378 is a screen extending preferably the full depth of the liquid to prevent light materials from being washed back into the path of the outer conveyor. The screen stretches from wall to wall of the tank between the chute and the outer conveyor and from a point slightly above the level of the liquid to a point just short of the lower conveyor.

This apparatus is operated to accomplish the above described step of the process as follows: The valve of pipe 359 is opened and heavy liquid is admitted to the tank through openings 360 until the level 374 is indicated on the sight gauge 366. Water is then run into the tank through the orifices 375 until the level 373 is reached. A continuous flow of water may be maintained through the machine through the pipe 375 and the overflow 362, if it is desired, or water may be added intermittently and as needed. The height of the parting liquid in the tank is regulated by the overflow 357. As the liquid is admitted it rises in the tank and in the box 353 until it reaches the open top of the cylinder 357 at which point it flows downwardly through the said overflow and through the valve and pipe 358 to the used liquid tank. The valve in the said pipe 358 may be kept open and a continuous flow of liquid pass into the chamber through pipe 359 and out of it through pipe 358, or the operation may be made intermittent, control being kept by observation of the sight gauge.

The tank having been filled to the proper level with liquid, coal is dropped from the conveyor into the chute 328, passing in four streams down the divisions 329 by which it is distributed across the width of the tank. The chute 328 may be placed on either side of the machine as is indicated in Figure 3e, an opening on either side being provided, that not in use being closed by a plate 376. The apparatus is started; the motors drive the two conveyors either at the same or at different speeds depending to some extent upon the quantity of material each has to handle. The coal, slate, and other admixed impurities drop into the water layer while still in the chute so that they are dispersed by the water before reaching the parting liquid; the splash made by their falling is dissipated and entrained gas is removed before they leave the chute. Passing through the water layer they enter the parting liquid, whose density has been selected to be between that of coal and that of slate. The coal floats on the surface of the parting liquid, the slate sinks down guided by the hopper 334 and, entering the conveyor pan, is picked up by the

scraper conveyor blades and carried toward the discharge. The coal floating at the interface of the liquids is picked up by the conveyor 343 and carried toward and onto the conveyor pan 346. The specific gravity of the liquid is preferably chosen to be only slightly lower than that of the middlings. The middlings are those portions of the mixture which contain in one lump both slate and coal. The middlings tend to sink only slowly in the liquid whereas the slate sinks instantaneously and the coal floats.

Each of the conveyors acts as a pump, the effect of which can be varied by the use of scraper blades of either solid or foraminous cross section, the number of openings in the said scraper blades being variable to secure pumping actions of different intensity. As the outer conveyor sweeps sunken material along its conveyor pan and up the incline toward the discharge, some of the entrained liquid tends to fall back through the orifices in the flights and that which remains is sucked out of the material as it is pushed over the wedge-wire screen 323. The slate is discharged through the hopper 322 into the trough 41 which forms a part of the apparatus 4 to be hereinafter described. The lower plate of the conveyor pan of the inner conveyor 338 is carried well beyond the pinion 345 and is then bent inwardly as indicated at 3460 so that the floated material will be swept on without jamming between the flights and the pan. By carrying the conveyor pan beyond the sprocket wheels 345 the chain is enabled to bend upwardly, and enough slack is provided therein so that when coal tends to jam the conveyor by taking up slack it may jump and release it without damage. The conveyor flights then sweep the coal up the inclined pan, over the wedge-wire draining screen 339, and eject it through the hopper 340 onto the trough 42 which forms a portion of the apparatus 4 to be hereinafter described. The liquid which is driven by the outer conveyor passes through the wedge-wire screen 323 downward through the chamber 324, outside the main wall of the tank through the passage 325 and the opening 326 into the chamber which is formed in back of the partition 336—337. The liquid which is entrained by the inner conveyor is swept up the inclined conveyor pan, passes through the wedge-wire screen 339, flows down the drain board 349, and is carried back to the chamber behind the partition 336—337. Sides 333—334 of the trough, together with the sides of the tank, form tubes 380—381 through which liquid from channel 325 and the chamber beyond 336—337 may travel to the receiving end of the machine, entering again into the separating chamber through the orifices 331 of the plate 330. There is thus maintained a constant motion of separating fluid and its superimposed sealing liquid from the receiving toward the discharge end of the machine. The length of the separating chamber, namely the distance between the plate 330 and the wedge 336—337 is such that the pieces of coal will have risen to the top of the separating liquid and the pieces of slate will have dropped to the bottom before the wedge has been reached, but the middlings, due to the selection of a parting liquid of only slightly lighter specific gravity, will be held in suspension, slowly sinking. The middlings rich in coal sink at a slower rate than the middlings poor in coal, due to their different densities, and a classification of the middlings takes place before the wedge is reached. The wedge then directs the richer mid-

dlings upward into the coal and the coal-poor middlings downward into the slate.

In Figures 3b and 3c is shown a means of varying the proportion of middlings which is thrown into the coal and a means which materially contributes to the production of coal with a standard ash content. In those figures 386 is the bottom of the conveyor pan; 383 is a plate; 382 is a hinge connecting the plate to the lip of the conveyor pan; 385 is a plate and 386 is a hinge connecting the plate 385 to plate 383; 387 are hook-shaped members which underlap the edges of the channel irons 377 for sliding movement. On the plate 383 at a point near the hinge 386 there is connected a lifting rod or cable 387 which extends upwardly between the conveyors and the wall of the tank and through a water seal box 368 mounted in the side of the tank to a point on the outside from which it may be manipulated. 389 are rods. By pulling up on one said rod the plate 383 will be lifted, and the plate 385 will swing toward the receiving end of the machine, the edge 386 of the wedge will have been raised and a greater proportion of the middlings will have been directed into the slate, producing a coal of decreased ash content. If, on the other hand, a coal of increased ash content is desired, a second rod attached at the lower end of plate 385 and projecting through the wall of the tank in the same manner may be manipulated to draw the plate 385 rearwardly and lower the angle 386. As shown in Figure 3h enough room exists between the edge of the conveyor flights and the wall of the tank to permit the passage of a rod, and by stationing and sealing tank 388 entirely outside of the wall 3 no interference between the conveyor and the rods will be experienced. The lower end of the rod may be attached to the wedge by a cable, as shown.

In Figures 3k and 3l is shown another means of adjusting the wedge. In those figures 3 refers to the tank; 390—390 are elongated boxes on the outsides thereof (a corner of which is shown in dotted lines in Figure 3); 391 are slots connecting the interior of the tank with the said boxes; 392—392 are links attached to the lower corners of the wedge; 393—393 are pins attached to the links, passing through the slots 391 and mounted in movable blocks 394; 395—395 are rods attached to the said blocks bored and screw-threaded; 396—396 are revolvable screws mounted in bearings attached to the sides of the boxes bearing at their heads pinions which mesh with pinions on shaft 398 which is mounted in the sides of the tank and projects through the wall of the box and a stuffing box 397; 399 is a hand wheel to turn the rod.

The operation of this apparatus is as follows. The hand wheel 399 is turned, rotating the intermeshed pinions and the rods 396 which extend or restrict the blocks 394 by reason of their screw fit with the interior of portions 395. As the blocks 394 are moved along the boxes, they push the link 392, which being attached to the corners of the wedge 385 move the wedge as indicated in part by the dotted lines of Figure 3k.

A brief description of the apparatus is as follows: The material to be separated enters through the chute into the receiving end of the apparatus and is collected by the hopper which encircles the section of the apparatus in which the actual parting of mineral and gangue takes place. The pumping action of the conveyors keeps the liquid in continuous circulation from the receiving end of the parting chamber to the

discharge end thereof. The upper conveyor sweeps the floats onto the conveyor pan, and the looseness of the conveyor chains permits the conveyor flights to jump and free themselves from any particles which tend to jam against the lip of the conveyor pan. The lower flight gathers the sinks and carries them out of the separating chamber. The middlings are carried by the current toward the wedge which forms the discharge end of the separating chamber and are divided according to the proportion of slate and coal they contain, those heavy because of large quantities of slate being thrown into the refuse, and those light because of usable quantities of coal being gathered in the floats. The separated materials are pushed by their respective conveyors over wedge-wire screens, or other suitable draining mechanism, which remove the majority of entrained liquids, and the materials themselves are discharged by the conveyors onto the collecting pans or troughs of the screen to be hereinafter described. The parting liquid which passes through the wedge-wire screens is returned along the sides of the machine and outside the separating chamber to the charging end of the machine and a continuous circulation is thus maintained. The level of heavy liquid is maintained at any desired point by the adjustable sealed weir at the end of the machine and the level of sealing fluid is maintained by the weir box on the side of the machine. Continuous addition and removal of liquid through the machine is thus possible, as well as intermittent additions as additions become necessary. Means are provided for blowing out the space beneath the conveyor pans and means are also provided for the removal of sludge from the bottom of the tank.

After the coal has been separated from the indigenous impurities, both are subjected to a vigorous scrubbing. In order to prevent the loss of any liquid by evaporation or otherwise the scrubbing is preferably carried out in a hermetically sealed chamber. A shaker screen is used in order to make possible the thorough washing of the coal, and the problem of transmitting power to the screen without opening the apparatus to the air was no small one. It was accomplished, however, by the means which are more fully described below. Briefly stated, the coal is carried through an hermetically sealed connection from the separating apparatus into the washing section where, constantly tumbled about by a shaker screen, it is subjected to an extremely vigorous washing whereby to remove all fine particles and substantially all the liquids that have been used in the process. The coal and slate are then dropped from the screen into the water baths of water sealed conveyors. The used liquid is run over a concentrating table, which tends to precipitate suspended solids, and to form large aggregates of suspended liquids, and the whole runs to the tank which forms the bottom of the machine, where a weir divides the liquids which contain only light suspended solids from the heavy sludge. The divisions are respectively drawn off and treated in a recovery system which will be more completely hereinafter described.

In the drawings Figures 4 to 4e are illustrative of this portion of the invention. In the figures, 4 refers generally to the washing apparatus; 40 is a shaker screen; 41 is a coal trough forming part of the said screen; 42 is a slate trough forming part of the said screen; 43 is a partition dividing the screen into two sections longi- 75

tudinally whereby to keep the separated coal and slate from becoming intermingled. 44 are strips of wood or some similar material which is capable of withstanding the abrasive action of the 5 coal and slate; 45 is a foraminous section at the charging end of the screen which permits the draining of liquid; 46 is a wedge-wire screen which forms the floor of that section of the screen which approaches the discharge end; 47 10 is a solid bottom to the screen at the discharge; 48 are discharge lips.

The construction of the screen is as follows: Angle irons 49 form the side frames of the screen and extend longitudinally from the feeding 15 troughs to the discharge plate 47. Dividing member 48 is also an angle iron extending from the troughs to the pipe; 490 are angle members connecting the side frames of the machine to the main frame of the screen; 491-491 are J-shaped 20 members having the taller leg of the J of considerable height; 492-492 are braces connecting the frame member 48 with the lower portions of the J-shaped member; 493 is a brace directly connecting the two J-shaped members; 25 494 is a splash guard running the length of the foraminous portion of the screen.

495-495 represent the support for the entire washing section; 496 is a tank forming the base of the machine; 497 is one wall of the tank; 30 498-498 are angle-shaped members forming channels with 497 and 496 respectively running lengthwise of and within the wall 497 and 496; 499 is the inclined bottom of the tank; 499 is a wall of the tank running lengthwise of the apparatus and forming a weir which divides the tank into two sections; 499 is the bottom of the tank beyond the weir; 499 is the outer wall of the tank, in this case placed considerably beyond the outer wall of the screen section; 499 is the 35 top of the said extended side; 499 is a rectangular opening, channel-shaped in cross-section, forming a seat for cover 495. By filling the channel-shaped member partly with water an effective gas seal is created. 496 is a wall forming in 40 part the outer wall of the apparatus and in part a wall dividing the two compartments of the tank; 497 are braces attached on the inside to channels 498; 498 is a bar supported by braces 497; 499 are side plates extending lengthwise 45 one on each side of the apparatus; 499 are side plates attached to the braces 492-493 running lengthwise on each side of the apparatus and overlapping the upright portions of channel members 498 inwardly thereof; 499 are drain 50 guards attached to members 499 to prevent the drainage from the screen from running into the channels 498; 499 are drain guards attached to the walls of the screen chamber and projecting within the channels formed at the edges of the 55 screen by angle members 49 and J-shaped members 499-499; 499-499 are walls of the screen section of the apparatus; 499 is the top of the apparatus; 499 is a cover for an opening in the top of the apparatus, said cover being formed 60 with one continuous flange 499; 499 are continuous channels in the top of the apparatus of size such that the continuous flange of the top 499 may be seated in the channel which, being partly filled with liquid forms an effective hermetical 65 seal. 499-499 are supports attached to and projecting at right angles to the outer legs of the J-shaped members; 499-499 are wooden spring boards; 499 are beams to which the spring boards are bolted; 499-499 are spring boards suspended 70 from the beams 499; 499 are weights hung from

the said spring boards; 499-499 are guides mounted on the frame 499 of the apparatus; 499-499 are buffer members approaching the counterweights; 499 is a shaft journaled in the frame 499; 499 is a wheel capable of being driven by a belt or similar power-transmitting means and, being keyed to the shaft 499, capable of driving the said shaft; 499-499 are eccentrics; 499-499 are driving rods attached to the eccentrics 499 and attached through connections 499 to the J-shaped screen frames; 499 are eccentrics placed on the shaft opposite to eccentrics 499 and on the outer sides of the frames 499 respectively; 499-499 are driving rods connecting the eccentrics to the counterweights 499. The 15 eccentrics, frame, and driving gear at the discharge end of the machine are shown broken away to indicate that in practice they are farther from the tank than was permitted to be shown in the drawings. 20

499-499 are headers which may be suspended from the beams 499 by connections 499 which comprise a band encircling the header having a hook to pierce an eye on a middle strip connected to the beams 499; 499 are pipes connected to the headers entering the washing tank through hermetical seals 499; 499 are valves in the pipes 499; 499 are pressure gauges operatively connected to the pipes 499; 499 are pipes connected horizontally to pipes 499; 499 are 25 spray nozzles affixed to pipes 499 so that the liquid in pipes 499 may be directed at the most efficient angle upon the material on screen 49; 499 are supports attached to the tank at spaced intervals; 499 are baffle plates supported by supports 499 extending transversely of the tank; 499 are channels at the bottom of the baffle to catch the drip and direct it to the sides of the screen into the channels formed by angles 49 and sides 499 of the frame; 499 are a series of supports extending transversely between walls 499-499 of the machine and inclined with respect to the horizontal; 499 is a plate supported on supports 499, extending substantially the full length of the machine, inclined by the inclination of supports 499 and terminating short of wall 499; 499 are supports which also extend between the wall 499 and wall 499 and which have inclination opposite to that of supports 499; 499 is a rifle plate substantially co-extensive with the length of the 50 machine and extending from the wall 499 to a line short of the wall 499. 45

In Figure 4a the screen is broken away at 499 to show the plain inclined plate 499; at 499 on the same figure the screen and plate 499 are 55 broken away to show the rifle plate 499 and the diagonal placement of the rifle bars. 499 is an outlet at the bottom of the tank 496 and at the juncture of incline plate 499 and weir 499; 499 is a pipe opening out of the portion of the tank 60 beyond the weir; 499 is a blow-out pipe through which water under pressure can be directed to discharge the sludge from the bottom of the tank through the orifices 499; 499 is a baffle plate at the end of the channel formed by members 49 and 499; 499 is a channel cut through members 49-49 so that any fluid in said channel member may be discharged upon the surface of and pass through a foraminous portion of the screen; 499 is a boot beneath the discharge end 49 of the 70 screen, separated from the tank as shown in Figure 4 and divided at its center by partition 499 which prevents the mingling of coal and slate. 65

In Figure 4e is shown the placement of the 75

spray nozzles so that a double overlap of spraying water occurs. By this arrangement the plugging or failure of one spray will not affect the washing of the coal because the two adjoining sprays will still overlap.

The operation of the apparatus which has just been described, considered in some detail, is as follows: Coal is discharged from the float conveyor of the separator onto the receiving pan 41 and slate is discharged from the sink conveyor onto the receiving pan 42. The longer leg of the J-shaped screen frames is, from the receiving to the discharge end of the screen, of decreasing height, whereas the shorter leg, that which is attached to the spring boards, is of uniform height. As a consequence, spring boards of uniform length are used and the screen is held on an angle. The screen is divided at its mid-portion by a partition which prevents the separated coal and slate from mingling. The driving mechanism reciprocates the screen at a rate which is consistent with the best performance and the materials are moved gradually from the receiving to the discharge end while being vigorously sprayed by a multitude of showers. The motion of the screen in combination with the sprays turns the coal repeatedly over so that all sides are exposed to, and thoroughly washed with, the cleansing liquid, effectuating a substantially complete removal of the liquid which the material has carried with it. In order to prevent the stoppage of one shower from leaving the section of coal unwashed, the showers are arranged in overlapping series as shown in Figure 4e so that each particle of coal is ordinarily sprayed by the water from three nozzles.

The receiving pans 41—42 of the screen are solid, thereafter the screen becomes foraminous either by the punching of holes through the plate, by the use of ordinary screens, or by other means. The final section of the screen is made of wedgewire in order to drain from the coal and refuse substantially all entrained water before delivery to the discharge pans 41 and the divided boot 462. The screen could be all of one type of wire but the arrangement shown produces superior results, all factors considered. Water is preferably used for washing the material and it is forced under pressure into headers 442 from whence it travels through the depending pipes to the spray pipes 448 and through the nozzles 449. The velocity of the spray is such that a considerable portion of the fluid is splashed from the material or the screen. The direction of the sprays would build up air currents passing from the receiving to the discharge end of the apparatus and considerable quantities of spray, containing recoverable liquid, would pass over the screen and down into the divided boot where it would be lost and contaminate the coal. To prevent this, baffle plates 451 are attached before each spray pipe so that the mist from the preceding spray will be caught upon the face of the baffle, run down into channels of 451, and be emptied into the channels formed by the members 49 and 461 of the screen from whence they will pass toward the discharge end and be issued through orifices 461 upon the wedge-wire screen. Substantially all liquids which are brought into the apparatus with the coal are removed from the coal and passed through the screens. In addition there is removed by the sprays a considerable quantity of fine solid particles, consisting mainly of earth and finely divided particles of

coal and slate, all below a certain size passing through the screens with the wash liquid.

When the liquids with entrained solids pass through the screens, they are prevented from reaching the sides of the tank by baffles 404, plates 419, 420, 421 and 408. It will be observed that plates 419, which are rigid with the frame of the machine, have openings through which pass the bars 403—402 of the screen, the openings in the wall of plate 419 being of size to permit the reciprocating motion of the screen. To prevent the discharge of liquid through that opening into the seal the plates 421, of a size adequate to cover the said openings in all positions of the screen, are mounted on the rods 15 402—403 and a baffle plate 420 deflects any fluid flowing down the side of plate 419 over and beyond the said plate 421. All liquid which passes through the screen, consequently, falls upon and runs down the inclination of plate 454, which is 20 a plate having a surface which permits the maximum desirable transportation of the liquid. The plate 454 is terminated short of the side wall and the liquids drop therefrom at substantially the top of riffle plate 456. They run down the 25 said riffle plate, the solids tend to precipitate, the globules of heavy liquid tend to become larger globules so that, when the liquids have finally passed the length of the riffle plate, a partial separation of the constituents has been effected. The 30 riffle plate is terminated short of the side wall 407 of the machine and the flow passes over the ends thereof and into the tank 406, all of whose bottom portions slope to the central low point in the neighborhood of outlet 459. The sludge and 35 some parting liquid settle in the vicinity of the opening 457 and the liquid which carries only comparatively fine particles of solid flows over the weir 410 into the other section of the tank, being pumped through orifice 458 to the second 40 settling tank, as is more fully elsewhere herein described. The sludge is pumped through orifice 457 to the third settling tank, which is elsewhere herein more fully described. If the sludge has collected so thickly at the orifice 457 that 45 the sludge pumps cannot draw it from the tank, a hose may be attached to pipe 459 and water under pressure used to force the sludge out of the chamber.

The screen is counterbalanced by the use of 50 spring board supported counterweights driven by oppositely placed eccentrics from the same shaft. The covers which give admittance to the tank are water sealed by the use of flanged covers which fit water filled channel members in the 55 machine casing.

In order to drive the screen, which is inside the tank, from the driving gear, which is outside, without permitting the escape of vapors, channel members partially filled with water are provided 60 on each side of the machine. The screen frame is made J-shaped, each J projecting into the liquid within the said channels, and being shorter than they by the length of the swing. The upper portion of the tank is then, so to speak, placed within 65 the hook of the J so that its lower edge is beneath the water level in the channel. The J-shaped frame, consequently, reciprocates within a water seal which effectively prevents the escape of gas, and the previously described construction of the 70 apparatus prevents the contamination of the liquid in the said channels.

From the screen the coal and slate drop into divided boot 462. Giving admittance to this boot are hermetically sealed covers 464. Hermetically 75

attached to the boot on the one side is liquid-tight conveyor box 51 and on the other side a similar conveyor box 52. The boot thus becomes two chutes, one for the coal and one for the slate. A description of one of these conveyors will suffice for both. 51 is the conveyor box in general, being a gas and liquid-tight tank made of metal or other suitable material; 53 is a hopper within the said conveyor tank having an inclined wall 54 to direct the material which falls from the screen into the conveyor box at the angle which offers the least interference with the descending flights of the conveyor; 510 is the inclined underside of the conveyor tank; 511 is a displaced portion of the said side; 512 is a foraminous section forming a continuation of the portion of the bottom 510, the portions 511 and 512 forming between them a space of a capacity adequate to take care of such liquid as may be discharged to them from the solids which are carried out of the tank by the flights. 505 is a conveyor pan; 506 are openings in the lower portion of the conveyor pan; 507 is a section of wedge-wire screen forming the bottom of the said conveyor pan at a point just short of the discharge lip thereof; 58 is the discharge lip of the conveyor pan over which the material is pushed by the conveyor; 59 is the supporting underlip of the conveyor tank; 513 is a flight conveyor; 514 are sprocket wheels over which the conveyor chains are trained; 516 is a motor mounted on the frame 517 of the conveyor; 518—519—520—521—522—523 are a combined power transmitting and speed reducing agency consisting, in the modification shown, of a series of alternate large and small gears connected either directly or by means of flexible driving means such as chains or ropes. 524 is a wheel driven by means 523 and keyed to shaft 525 on which are keyed the sprocket wheels 514; 526 are bearings on the tank which support the rod 525; 527 are parallel bearing blocks; 529 is a shaft journaled at one end with a loose fit in the said bearing blocks 527 and at its other end in complementary bearing blocks, not shown, at the other side of the conveyor box. 530 is a rod fastened at one end to the shaft 529 and having at its upper end a screw-threaded nut 532; 531 is a screw-threaded rod making operable screw-threaded contact with the nut 532. One of these rods is attached to each end of the shaft 529. The rods 531 are mounted on a rod which transverses and is attached to the sides of the tank. The conveyor may jump away from the pan due to the loose fit of the blocks and may be manually adjusted by nuts 532. 541 is an opening in the base of the section 511 to which is attached a pipe, not shown, connected to the lower section of the conveyor whereby to return the liquid drained from the whole by the wedge-wire screen to the conveyor box at a lower point; 542 is an inlet pipe and valve through which liquid can be run into conveyor box; 543 is an outlet pipe and valve at the bottom of the conveyor which permit the drawing off of such sludge as may form there. The pipe 543 is connected either to a waste pit or to the settling tank, which is elsewhere herein more fully described. 544 is a liquid box outside of the machine; 545 is an overflow pipe within the said liquid box.

The operation of the apparatus is as follows: 70 Coal is dropped from the discharge lip 48 of the screen through the divided boot and the hopper. The hopper and the conveyor tank are filled to the level 546 with water or other suitable liquid. The coal is discharged into the water therefor above 75 the hopper level and is directed by the inclination

of the chute 54 to a place in proximity to the descending flights of the flight conveyor. The coal passes through those flights and directly to the conveyor pan where it is picked up by the ascending flights, drained of liquid by passage 5 over the wedge-wire screens and discharged over the discharge lip 58. The liquid level in the apparatus is kept at the level 546 so that no fumes or liquids coming over the discharge end of the screen will be able to escape into the air. The 10 liquid which is drained through the wedge-wire screen fills up the space between the conveyor pan and the tank and thereafter passes through the screen 512 into the space below from which it is drained off by pipe 541 which returns it to the 15 bottom of the conveyor tank or elsewhere. Means are provided, not shown in these drawings, for blowing out the space between the conveyor pan and the bottom of the tank and consist of a nozzle through which water can be forced under pressure 20 at 459 as has hereinbefore been described for other apparatus.

The liquids which wash the coal in the washing section remove from the coal and slate substantially all the heavy liquid and the fine particles 25 which are produced by abrasion or which are carried through the machine. In the settling tank at the bottom of the washing apparatus the liquid with fine suspensoidal matter is separated from the heavy sludge by the weir. The heavy sludge 30 is pumped from the bottom of the tank through pipe 457 to settling tank 1, shown in Figures 7 to 7c, and the liquid with light suspensoidal matter is carried through pipe 458 to the main settling tank 6, shown in Figures 6 to 6c.

The system contains three settling or separating tanks interconnected, of which the first, located in the base of the washing section, makes a preliminary division between sludge and liquid containing light suspensoidal matter, the second, 40 called for purposes of differentiation the main settling tank, separates the comparatively light suspensoidal matter from the washing liquid and the third, called for convenience the sludge trap, receives the sludge from both the first and second tanks. The statement has frequently been made in the art that it is impossible to separate coal sludge from washing liquid by any static method. It is believed that the method herein described for accomplishing this result is the only one 45 which has ever been successful.

In Figures 6 to 6c which illustrate the so-called main settling tank or separator, 6 indicates the separating apparatus as a whole; 458 is the discharge end of the pipe which carries the liquid with light suspensoidal matter from the primary settling tank; 61 is the top of the tank; 610 is a tubular member which passes through and fits an opening in the top 61; 611 is an angle iron which joins the tube 610 to the top 61 with an 60 hermetical joint. Joining may be by welding or other suitable hermetical sealing. The tubular member extends toward the bottom of the tank. 612 are openings in the sides of the tubular member above the operating water line; 613 is a 65 cover to the tubular member 610 pierced by the discharge pipe 458; 62 is a truncated conical bottom to the tank; 621 is a sump connected to the truncation of the cone. This sump may be considered to be made by passing a plane di- 70 agonally through a cylinder. 622 is the diagonal plane dividing the "cylinder" 621 and forming a diagonal bottom on the sump which directs the solids which collect toward the discharge pipe 620 and valve 623; 624 is a pipe carrying water 75

under pressure for use in dislodging sludge from the bottom of the sump 621 if and when the said sludge becomes too solid to be moved by pumps; 625 is a rod journaled in bearing 626 in plate 622 and passing through stuffing box 614 in cover 613; 616 is a handle attached to the upper end of the rod 625; 628 are arms attached toward the bottom of the rod 625 so as to be rotatable by and with the handle 616 and rod 625; 627 are scrapers diagonally placed on the arms 628 so that their movement will dislodge collected sludge from the conical bottom 62 and push it toward the sump 621; 617 are water seal covers whose construction is similar to the water seal covers which have been elsewhere herein described; 630 is an angle member of depth which increases from one side of the tank to the other, welded or otherwise connected to the inside of the tank 6 toward the top thereof; 631 is a wooden weir strip of circular form attached to the angle member 630; 633 is a discharge box at the lowest point of the channel formed by tank 6 and angle member 630; 615 is a pipe connected to the said box 633; 640 is a circular channel suspended from the top 61 of the tank within the weir and having a lip 641 which is slightly lower than the top of the weir 631; 642 are pipes projecting inwardly from the channel 640 toward the bottom of the tank; 65 are supports for the tank comprising metal legs attached to the tank and supported upon the box.

The operation of this apparatus is as follows: The liquid containing light suspensoidal matter in greater or less quantities enters the tank through pipe 458 and tube 610. It passes outwardly beneath tube 610 tending to throw toward the bottom the heavier suspensoidal matter and to rise toward the surface, whose level is established by the weir 631. The vibrations caused by the plunge of the water from the pipe 458 into the body of water in the tank are largely spent within the tube so that the liquid within the remainder of the tank is comparatively quiet. The channel which is formed between the weir and the shell of the tank is sloped and increased in size toward the outlet. The liquid which flows over the weir follows the slope downwardly to the box 633 and is carried by the pipe 615 back into the headers 442 where it is used again for the washing of the solid materials on the screen. Light scum tends to float on the surface of the liquid within the tank and the direction of the liquid currents within the tank would in the normal course wash this scum over the weir. The openings 612 are vents to relieve interior pressure. Interposed between the weir and the pipe is the scum gutter 640. As the scum, floating on the surface of the water and being drawn by the current toward the weir, floats over the edge 641 of the scum gutter, which is slightly lower than the weir and contacts the side of the scum gutter, the scum tends to precipitate therein. As it is precipitated, its apparent specific gravity increases to the point where it will follow the tubes 642 downwardly into the lower section of the tank where it will settle on the bottom and be drawn off with the sludge. The sludge which concentrates in the bottom is from time to time scraped toward the sump and pumped through valves 623 and pipe 628 to the sludge trap. If the pipe becomes blocked it can be cleared by an injection of water through pipe 624.

In Figures 7 to 7c is shown the arrangement of the sludge trap and the still. The function of the sludge trap is to separate out the water with light suspensoidal matter and return it to the

main settling tank for further treatment; secondly to separate out isolated heavy liquid and return it to the heavy liquid storage tank; and thirdly to inject all remaining liquids and solids into a still for the recovery of any parting liquid which may be therein contained.

In those figures, 457 and 620 indicate pipes leading from the first and main settling tanks, respectively. 7 refers to the sludge trap taken as a whole; 71 is the pipe through which passes the sludge from pipes 457 and 620; 710 is a sight glass held in liquid and gas tight relationship between plates 711 and 712; 713 is an inlet pipe of diameter considerably greater than that of 71 in order that the discharge material may be reduced in velocity and find easy entrance to the sludge trap and not fill up the sight glass 710; 714 is a tubular member inside the tank through which the material is discharged; 715 is a water seal covering of the type which has been hereinbefore described; 716 is a circular weir within the tank toward the top thereof which forms with the walls of the tank a channel having an inclination sufficient to drain such liquids as pass over the weir to the discharge box 717; 718 is a circular baffle plate within the weir. The lower edge of the baffle plate is beneath the liquid level in the apparatus, and in close proximity to the weir so as to form a substantially complete vapor seal. 719 are a series of valved openings leading into the tank at various levels; 720 is a header connecting the said valved openings; 721 is a draw-off pipe leading from the header; 722 is a glass peep slot through which the contents of the tank may be observed substantially throughout its height; 723 is a pipe mounted in the side of the tank; 724 is a section at right-angles thereto; 725 is a liquid-tight ball joint; 726 is a section of pipe movably connected to section 724 through elbow 727 and ball-joint 725; 728 is a block attached by rod 729 to pipe 726 and through connection 730 to rod 731 which passes through a stuffing box in the top of the tank; rod 731 is attached to a slider 732 operably mounted for vertical sliding movement between guides 733—735; 734 is a rack affixed to the face of slider 732; 735 is a pinion mounted on rod 736 which is journaled in bearings 737 which are mounted on the supports 738 which are attached to the tank; 739 is a wheel, chain or otherwise operated, which is attached to shaft 736. By rotation of the wheel 739 the rod 731 may be raised or lowered, raising or lowering the pipe 726 in conformity; 740 is a conical bottom to the tank; 741 is a valve in pipes 742 which connects the sludge tank with the still 8; 743 are supports for the tank.

The operation of the apparatus which has just been described is as follows: The sludge from the sources of sludge supply is brought through the sight feed glass 710 and pipe 713 into the tank where the sludge settles to the bottom, the heavy liquid forms a layer on top of the sludge, and water is separated out on top of the heavy liquid. The condition of the ingredients is such that in many cases so clear a separation is obtained that it is possible to draw off part of the liquid by decantation, substantially clear liquid passing over the weir and out through the pipe 717 from whence it may be returned to the settling tank, to the main settling tank, or may be discharged. Between the layer of sludge at the bottom and the layer of light liquid at the top there may form a layer of the heavy parting liquid of sufficient purity to be withdrawn for storage or immediate

reuse. The separation of this intermediate layer is accomplished by the movable pipe 726, which is adjusted up or down by viewing the tank through the sight glass 722. As the layer of intermediate liquid becomes thinner the orifice in pipe 726 is adjusted so that none of the layers on either side of the liquid is taken. In this way the intermediate layer may be drawn off without disturbing the adjacent layers. After the intermediate layer has been drawn off, or before, clear liquid toward the top of the tank may be withdrawn to any desirable height through the openings 718 and the header 720. By observation through the sight glass 722 the operator selects the valve to whose level he wishes to reduce the liquid in the tank, opens that valve, and the liquid drains by gravity or by the use of a pump into pipe 721, and is carried off for reuse in the headers, to the settling tank, or elsewhere. When the relatively clear liquids have been withdrawn from the tank, the valve 741 is opened and the remaining material is forced into the still 8, with the aid of water jets 754. When the sludge trap has been cleared, the valve 741 is closed and the sludge trap is refilled.

In Figures 7 and 7c, 8 refers to a steam still as a whole; 81—82 are outer and inner walls of the still, respectively, braced at points by members 83 which may encircle the still but are preferably open in parts to permit the drainage of water from the upper to the lower portion of the jacket; 84 is a steam jacket at the base of the still; 85 are openings through which steam may be injected directly into the still chamber; 86—87 are points for the admission of steam and 81—87 are points for the removal of steam and condensed water; 88 is an opening at the top of the still which connects through pipe 89 with the condensers which are to be hereinafter described; 818 is a discharge pipe at the bottom of the still; 811 is a valve in the said pipe; 812 is an opening in the top of the still; 813 is a removable closure therefor, held in hermetical contact therewith by bolts 814 or by other suitable means; and 815 are supports for the still; 820 is a water line; 821 are pipes leading from the water line to the base of the still to furnish means for making fluid the solid residue from the distillation and for ejecting said residue through pipe 810; 822 is a vent line passing through the top of the still; 823 is a valve in the vent line 822; 758 is a vent line communicating with the interior of the sludge trap through the top thereof; 751 is a valve in the vent line 758. Vent line 822 connects with vent 750. 752 is a vent pipe to which both 822 and 750 are attached. This vent 752, together with all the other vent pipes in the apparatus, are directed to a scrubbing system such as a spray of water which removes entrained vapors therefrom. The scrubbing system being of standard construction is not shown, and the vents in general are shown for convenience as open at the upper end. 753 is a water supply line encircling the base of the sludge trap; 754 are blowout lines penetrating the shell of the sludge trap at the base thereof so that the heavy residue from the sludge trap may be forced through the valve 741 into the still.

The operation of the still is as follows: A charge having been dropped through the pipe 742 into the still, steam is admitted through the openings 88 to the jacket and directly to the charge through the openings 85. Preheating before admission of the steam to the charge is sometimes advantageous. The heavy liquid and water contained in the still are vaporized at a temperature

below that of decomposition of the liquid and pass off together with the steam through opening 88 and pipe 89, which directs them to the condensers. When the last of the heavy liquid has been recovered, the valve 811 is opened and 5 water pressure from source 828 carries the waste contents of the still through the pipe 810 to its destination. Steam pressure can also be used to aid ejection of the sludge.

Figures 9 and 9a show the condenser system. 10 Two standard sections of radiator, each containing four units, constitute, we have discovered, an excellent condenser when used in combination with a single fishtail spray for each unit. In the drawings 910 are the four units of one standard 15 radiator section and 911 are the four units of a second standard radiator section. 912 is a water supply pipe; 913 is a valve therein; 914 are four pipes extending above the radiator sections; 915 are single sprays above the units of the radiator 20 sections.

The apparatus functions as follows: Through pipe 88 is carried the distillate from the still which finds its way through the radiators in the direction of the arrows. Each radiator section 25 is sprayed with cold water and the distillate is condensed and is directed through pipe 801 to the cooler 85.

In Figure 10 is shown a type of joint used throughout the apparatus. It will be appreciated 30 by engineers that the majority of pipes in this system carry suspensoidal matter in addition to liquid and that the suspensoidal matter will tend to precipitate out wherever a joint is found. In order to make possible the cleaning of all such 35 joints, they are constructed as follows: *t* is a pipe line; *m* is a pipe joint or elbow; *n* is a pipe line; *o* is a pipe screw threaded at *o*—*o* and covered by a removable cap *q*. When joint *m* tends to collect too large a deposit, the cap *q* is removed 40 and a hose bearing water under pressure is attached to the screw thread *o*—*o*. When the water is turned on it blows any collected silt or deposit away from the joint. The hose is removed 45 and the cap *q* is replaced. By directing the flow of liquid from pipe *m* through pipe *t* the silt piles up in the pipe *o* until it is substantially full. Thereafter the erosive effect of water is borne by the collected silt, not by the piping.

In Figures 8, 8a, and 8b is illustrated an apparatus for determining the percentage of coal in the sinks and the percentage of slate in the floats, in other words, for determining the ash content of the clean coal as delivered by the system so that the middlings may be divided to the best advantage. In these figures 75 indicates generally a long trough, made preferably of some chemically resistant metal; 758—759 are walls which divide the trough into a series of chambers; 751—751 are trays having foraminous bottoms 50 752 and preferably solid sides, the shape of the trays conforming substantially to the shape of the compartments of the trough. Each compartment of the trough is provided with a tray. The trays are pivoted at one end to the trough, 55 conveniently by a method shown in Figure 8c. 753 are U-shaped members attached by welding or otherwise to the outer edge of the tray 751; 754 is a pipe or other circular member attached to or forming the edge of the trough 75; 755 are 60 bolts passing through the ends of U-shaped members 753; 756 are handles attached to the lip of the tray 751 opposite to the pivot; 757 are stops so placed that they contact the edge of the said trays and prevent their making contact with the 65 75

bottom of the trough 15; 158 are pipes and valves leading to each compartment for drainage purposes; 159 are stop bars placed approximately midway of and running the length of the sides of the trays; 160 is a scoop having a foraminous bottom 161 and a handle 162; 163 are means for supporting the trough; 164 is a shelf running lengthwise of and before the trough and having an edge 165 to prevent the escape of liquid and a drainage channel 166 and pipe 167 for such liquid; 168 is a screen to prevent the escape of solids down the drain. 170 is a means, such as a steam line, to regulate the temperature of the bath.

In normal operation the apparatus will have possibly ten compartments. Each compartment will be filled to equal depth with a liquid. 169 shows a liquid level. For example, the first compartment will contain a liquid of specific gravity 1.9; the next will have a specific gravity of 1.85; the next 1.8; the next 1.78; the next 1.76; etc., the specific gravities being chosen to give the maximum information with the particular coal or other mineral being treated in the process at the moment. A sample is taken, for instance, of the coal which is discharged from the water-sealed conveyor and a weighed portion thereof is put into the first compartment. Assuming that the specific gravity of the compartment has been correctly chosen for the first test, a considerable portion of the charge will sink and the remainder will float. The operator then takes scoop 160, inserts its nose within the tray, as shown in Figure 8a, slides it across the runners which are at equal depth in each compartment and withdraws the floats. The liquid is allowed to drain back through holes 161 in the foraminous bottom of the scoop and the floats are placed in the next tank, whose specific gravity is somewhat lower. This procedure is continued until the sample has been divided according to specific gravities. By pulling on the handle 166 the trays 151 may be pivoted about pipes 154, draining through holes 152 back into the trough 15 and the sunken material may be dumped into a pan or other suitable means placed on the table 164.

The system is first calibrated by making ash determinations with the particular type of coal which is being separated, a determination being first made of the specific gravity of the incoming matter to determine the specific gravity of the parting liquid to be used in the tank 3. After operation has commenced, samples are taken of both the sinks and the floats and ash determinations are run to calibrate the system. Thereafter determination of specific gravities is made by plotting subsequent tests against the control. In this way the coal content of the slate and the slate content of the coal may be determined and from the information obtained adjustment made to vary the percentage of slate in the coal as hereinbefore described. In each instance there will be given an accurate check on the distribution of middlings since it will be understood that, if the specific gravities range between that in which pure coal alone will float and that in which slate alone will sink, the specific gravities of the samples which sink in succeeding baths will be in direct relation to their respective quantities of coal and slate. Zinc chloride solution is a satisfactory agent for use in this apparatus because it can be easily diluted to precise specific gravities, but any other satisfactory liquid may be used. Having determined the distribution of the middlings as actually distributed by the apparatus, a prompt change can be made in the setting of

the apparatus so that another and more favorable distribution can be made if such is desired.

On the key figure a piping diagram is shown in which, for convenience sake, certain of the valves have been indicated by the numerals V1, V2, etc. Referring to that diagram, the parting section is filled with liquid by opening valve V14 and by means of a pump P2 and pipe line forces the parting liquid into the chamber 353 and the tank 3 until the level of weir 357 is reached. Thereafter the level of the liquid is maintained by overflow through the weir 357, valve V8, and pipe 358 to the used liquid tank. The flow can be kept constant or additions of fluid can be made from time to time by the use of valves V6 and V14. Once the liquid has attained its level valve V14 may be closed, shutting off the supply of parting liquid and valve V8 either closed or left open as is convenient. If at any time it is desirable to drain the tank 3, valves V8, V5, and V14 will be closed, valves V6, V7, and V20 opened and the tank drained directly to the storage tank 364. If sludge is to be removed from the bottom of the tank drainage will be through valves V6, V5, V4, and pump P2 into sludge tank 7.

If it is desired to remove the sludge from the bottom of section 4, the valve V3 will be opened, valves V2 and V4 will be closed and the sludge will be pumped directly to tank 7. If it is desired to take the sludge from tank 6, valves 623 and V2 will be opened, valves V3 and V4 closed and the sludge will be pumped to the tank 7. The liquid from separator 26 will be run to either the new liquid storage or the used liquid storage by the proper manipulation of valves V13 and V12.

The apparatus which has been described offers an excellent method of accomplishing the process. It is not, however, the only apparatus which can be used to accomplish the process and considerable modification both in general and in detail can be adopted.

In the parting step of the process the liquid used is preferably organic and of the halogenated hydrocarbon type. However, the process is not limited to such agents since any separating agent which has proper specific gravity and is properly inert to the materials which are to be separated may be used. The factors which are desirable are that a material shall have high boiling point in order that there shall be low vapor pressure at working temperatures, low melting point in order that it may be liquid at working temperatures and the expense of keeping it fluid by heat avoided, low solubility in water in order that it may not become contaminated with the sealing liquid and may not be carried out on the separated material, stability under the conditions of operation including stability to agents, air, light, and heat, low hydrolyzing capacity, low toxicity in order to avoid injury to operators when the apparatus is cleaned, low viscosity, and low cost. Among the compounds which have been found useful are the following:

Pentachloropropane, 3,4 dibromo 2,2 dimethyl butane, iodobutane, hexachloropropane, 1 chloro 3 bromopropene, 1 bromo 2,3 dichloro n-butane, 1 iodobutane, 1 chloro 1 bromoethane, 1,3 dibromo 2,2 dimethyl propane, 2,4 dibromopentane, pentachloroethane, 2,3 dibromopentane, 1,2 dibromo 2 methyl butane, 1 chloro 2 bromoethane, 2 iodopropane, 1,5 dibromopentane, 1,4 dibromopentane, heptachloropropane, 1,2 dibromopentane, 1 iodohexane, 2 chloro 1 iodobutane, 1,1 chloro 1 bromoethane, 1,1 dibromo 2,2 methyl

- 5 propane, 1,4,7 tribromoheptane, 1,1,1 trichloro 2-bromopropane, 2,2, dibromopropane, 1,2 dibromo 2 methyl propane, 1,3 dibromobutane, 1,4 dibromobutane, 1,2 dibromobutane, 1,3 dibromo 2-methyl propane, 2,3 dibromobutane, 2,2,2 trichloro 1 bromoethane, 2 chloro 1 iodopropane, 3 chloro 1 iodopropane, 3 chloro 1,2 dibromobutane, iodoethane; 2 fluoro 1,1,2,2 tetrabromoethane, dichlorobromomethane, 1,2 dibromopropane, 1 chloro 2,3 dibromobutane, 1,3 dibromopropane, chlorobromomethane, tribromo 2 methyl pentane, 3 chloro 1,3 dibromopropane, dichloriodopropane, 1,6 diiodohexane, trichlorobromomethane, 1 chloro 1 iodoethane, 2 chloro 1,2 bromopropane, 1,3 dichloro 1,2 dibromopropane, fluoro 1,2 dibromopropane, 1,1 dibromoethane, 2,3 dichloro-1,2 dibromopropane, 2 fluoro 1,1 dichloro 1,2 dibromoethane, 1 chloro-1,1 iodoethane, 2 chloro 1 iodoethane, 1,2,2 tribromo butane, 1,2,3 tribromo butane, 1,1,2 bromobutane, 1,2 dibromoethane, 1,5 diiodopentane, 2 bromo 2 iodopropane, 2,3 dichloro 1 iodoethane, 1,2,3 tribromobutane, 2,2, difluoro 1 iodoethane, 1,1 difluoro 1,2 dibromoethane, 1,1,2 trifluoro 1,2 dibromoethane, 1 fluoro 1,2 dibromoethane, 2 chloro-1,2 dibromoethane, methyl iodide, 1,1 dichlor 1,2 dibromoethane, 1,2 dichlor 1,2 dibromoethane, 2,2,2 trichloro 1,1 dibromoethane, 1,3 iodobutane, 1,4 iodobutane, 2,2 difluoro 1,1 dibromoethane, 1,2,2 tribromopropane, 1,4,7 triidoheptane, 1,1,2 tribromopropane, trichloro iodomethane, 2,2 dichloro 1,1 dibromoethane, 3 chloro 1,2,2 tribromopropane, dibromo dichloromethane, 1,2,3 tribromopropane, 1,2,2 trichloro 1,1,2 tribromoethane, dibromo chloromethane, 2,2 diiodopropane, chloro iodomethane, dichloro iodomethane, dichloro tribromobutane, 1,2 diiodopropane, 1 bromo 1 iodoethane, 2 bromo 1 iodoethane, 1,1,4,4 tetrabromobutane, methylene bromide, 1,1,2,3 tetrabrom 2 methylpropane, 1,1,2 trifluoro 1,2,2 tribromoethane, 1,3 diiodopropane, 1,1,2 tribromoethane, 1 chloro 1,1,2 tribromoethane, 1,1 difluoro 1,1,2 tribromoethane, 1,1,2 tribromoethane, 1,2 dichloro 1,1,2 tribromoethane, 1,2,2,3 tetrabromopropane, 2 fluoro 1,1,2 tribromoethane, 1,4 dichloro 1,2,3,4 tetrabromobutane, 1,1,2,3 tertabromopropane, 1,1 diiodoethane, bromoform, hexabromobutane, 1,1,1,2 tetrabromoethane, iodobromomethane, 1,1,2,2 tetrabromopropane, 1,1,2,2 tetrabromoethane, 1,1,2,2,3 pentabromopropane, diiodo chloromethane, pentabromoethane, methylene iodide, 1 chloro 1,1,2,2 tetrabromoethane, perchlorethylene, 2,3 dibromopentene-2, 1,1,2,3,3,3 hexachloropropene-1, 2-iodopropene-1, 2 chloro 1 bromoethene, 3-iodopropene-1, 1,3 dibromo 2 methylpropene-1, 1,2 dichloro-1 bromoethene, 1,2 dibromobutene-1, 2,2 dichloro 1 bromoethene, 2-chloro 3-iodopropene-1, 1 chloro 3 iodopropene-1, 1,2 dibromopropene-1, 3 iodopropene-1, 1,1,2 chloro 1 bromoethene, 1 iodopropene-1, 1,3 dibromopropene-1, 1,3 dibromopropene-1, 2 chloro 1 iodoethene, 1 chloro 1,2 dibromoethene, 1,2 dibromoethene, 2 fluoro 1,1 dibromoethene, 1,2 difluoro 1,2 dibromoethene, 1,2 dichloro 1,2 dibromoethene, 1,2,3 tribromopropene-1, 1,2 diiodopropene-1, 2 bromo 1 iodoethene, fluoro tribromoethylene, tribromoethylene, 2,2 dibromo 1 iodoethene, 1,2 iodoethene, iodocyclohexane, 1,2 dibromocyclohexane, 3,4 dibromo 1,2 dimethylbenzene, 3,4 dibromotoluene, 2,6 dibromotoluene, 2,5 dibromotoluene, iodobenzene, 1 iodo 2 chlorobenzene, 1,3 dibromobenzene, 1,2 dibromobenzene, trichlorethylene, 4 chloroethane, and carbon tetrachloride.

The list has been mainly directed to halogenated hydrocarbons but it is to be understood that any liquid having the desirable qualities set forth above can be used so far as the mere separating step is concerned.

Kerosene, benzene and naphthalene and other hydrocarbons, particularly those of low boiling point and vapor pressure can be used as diluents to alter the specific gravity of parting liquids. Metallo compounds such as mercury, or antimony bromide could be used at suitable temperatures and under other proper conditions of operation.

The specific gravity of the parting liquid used will be between the specific gravities of the mineral and gangue which are to be separated. The separating liquid within the tank will be covered by a sheet of water or other liquid inert thereto which will serve the purpose of preventing evaporation of the liquid and of rejecting parting liquid which gathers on the floating material. The liquids may be so arranged as to fill the whole tank or to fill only a portion of the tank.

It is advisable to design the chamber in which the separating actually occurs with particular reference to the mineral which is to be treated. For example, if a finely divided iron is to be separated from its gangue, a longer chamber would be required in order to give all the fine particles an opportunity to respond to the parting action of the liquid. On the other hand, in those cases where no rafting of the particles is observable and separation is quickly and completely carried out, a short chamber may be used. Another method of accomplishing this variation is to vary the speed at which the liquid within the separating chamber travels, thereby varying the length of time which the material is allowed to separate.

The parting liquid can be of one liquid or it can be a mixture of completely miscible liquids of different specific gravities. Thus, a mixture of $C_2H_5Br_4$ and $C_2H_5Cl_4$ will give a range of specific gravities from 2.39 to 1.59. This principle can be availed of to adjust the specific gravity of the liquid to one in which the middlings will sink at a rate most favorable for separation by the apparatus. This selection of specific gravity may be availed of to secure particular separation of the middlings in a machine provided with an immovable wedge.

The velocity with which the conveyors travel in this apparatus determines the point to which the middlings will have sunk at the moment they contact the wedge. Thus, by speeding up or slowing down the conveyors the velocity of the liquid can be increased and a variation in the slate containing middlings included with the coal accomplished. By speeding up the conveyors the liquid will travel faster, the middlings will not have sunk so far and a wider percentage of low-coal middlings be incorporated with the coal. By slowing down the conveyors the parting liquid will travel more slowly and only the richer coal middlings be incorporated with the coal.

A third method of varying the slate content of the coal and the coal content of the slate is by adjusting the point of the wedge up or down. Means for doing this have been described in the specification.

These three methods of dividing the middlings may be used separately, with one another, or all together and when so used give the very greatest flexibility to the system.

This description has been more or less spe-

cifically directed to the separation of coal from its indigenous impurities. The process is not limited to coal, however, and it is applicable to the separation of minerals in general, although it can be readily understood, as elsewhere herein pointed out, that to secure the best results with a particular mineral the speed of the liquid medium, the density of the parting liquid, and the length of the separating chamber may be varied. Substantially all minerals are obtained in their native condition in admixture with indigenous impurities. In some cases the mineral is the heavier and the gangue the lighter. In such case the gangue will float on the surface of the parting liquid and the mineral will sink to the bottom and be carried out by the lower conveyors. In other cases, as in the case of coal, the reverse is true. The design of the conveyor system may advantageously be altered to accommodate the amounts of mineral and gangue which is to be expected with a particular process. Another variation which must be considered by the engineer in treating different minerals is that the specific gravities of the minerals themselves vary. Thus, anglesite varies from 6.1 to 6.4; anthracite coal varies from 1.3 to 1.7 and bituminous coal varies from 1.1 to 1.5. Among the minerals which can be separated from their gangues by this process are the following: asbestos, bituminous coal, anthracite coal, chrysocolla, garnierite, quartz, feldspar, black diamond, mica, fluorite, wad, siderite, calamine, rhodochrosite, diamond (gem grade), cyanite, limonite, azurite, psilomelane, malachite, garnet, corundum, sphalerite, willemite, chalcopyrite, smithsonite, witherite, rutile, stannite, chromite, barite, tetrahedrite, ilmenite, energite, pyrrhotite, covellite, pentlandite, molybdenite, braunite, pyrolusite, bornite, hematite, pyrite, magnetite, franklinite, millerite, zincite, chalcocite, cuprite, scheelite, anglesite, vanadate (lead), cerussite, heubnerite, cassiterite, wolframite, galena, iron, niccolite, ferberite, cinnabar, copper (native), silver, platinum, and gold.

Many modifications of the scrubbing process are possible. In addition to the sprays herein shown, sprays may be directed from beneath the screen to assist in the scrubbing of the coal. The concentrated table or rifle board can be omitted, but its omission is inadvisable if preferred results are to be obtained. It has been stated in the literature that no static means has been designed which is capable of separating coal size from wash water. It is believed that the method of separation which is disclosed represents the first successful separation of wash liquids and solids by a semi-static process. In this separation the rifle plate plays a valuable part by tending to precipitate the fines, coagulate the minute globules of parting liquid, and separate the water. This, in combination with the three weir-type settling tanks, makes a system of great efficiency from which the recovery of heavy liquid is almost quantitative. The weir can be omitted from the so-called sludge trap and the water which collects in the upper layer drained off solely through the connected draining valves on the side thereof. The efficiency of the first two tanks is such that it is sometimes possible to omit the sludge trap and direct the sludge from the first two tanks directly to the still for steam distillation.

Any satisfactory method of distilling may be used to remove the heavy liquid from the sludge. The one illustrated is shown because it produces excellent results.

The condenser of radiator type is an installation the cost of which is about one-tenth that of a standard condenser system capable of handling an equal quantity of condensate, and which saves enormous quantities of water.

The coal may be given any available pretreatment, e. g. prewetting, before being entered in this apparatus.

The cooler whose function is to reduce the temperature of the condensate is of standard design and construction. It is shown diagrammatically as a sleeve about the pipe which connects the condenser 9 with the water separator 86, the sleeve being closed at its ends and provided with an inlet toward one end and an outlet toward the other end for a stream of cooling liquid.

In the water separator the parting liquid and water, being immiscible and of different specific gravities, separate out. The parting liquid is run to the storage tanks and the water is preferably returned to another section, for instance, the main settling tank.

The storage system shown, wherein a new liquid tank overlies a used liquid tank, is a convenient one but not essential to the process. Other systems of storage could be used. Most such systems, however, would involve the principle of adding fresh liquid to the used liquid as needed. The addition of new to used liquid may take place in the separating tank, in the storage tank, or elsewhere as the engineer sees fit.

In actual operation the system is in almost perfect balance. Substantially all the water used is recovered and returned to the system, and substantially all the parting liquid used is returned to the system. It may be stated with complete accuracy that the system requires a minimum of attention, and a minimum of operating fluids and yields results which are equal to or better than those which have heretofore been considered theoretically possible. For example, in Taggart "Handbook of Ore Dressing" the statement is made that the standard use in the laboratory for determining that degree of separation which utilizes the last useful quantities of coal and eliminates the last useless quantities of slate is the sink and float method as performed in a beaker. Taggart also states that that perfection of separation is impossible of attainment, and his statement was correct as applied to all previous systems. By virtue of the development of this process and apparatus, however, the perfection of separation which Taggart mentions as attainable in a beaker is accomplished on a commercial scale.

An advantage of this invention as a whole is that there has been produced a coal cleaning process based on the use of a parting liquid which is capable of competing with the highly developed processes previously used in the art. Another advantages of the invention is that, by the processes set forth, the losses of expensive separating liquid are reduced to a point that makes the process commercially feasible and actually makes it considerably less expensive than the older processes. Another advantage of the invention is the rapidity with which the process can be operated with satisfactory results. A unit having only four square feet of separating surface was tested for speed and satisfactorily separated 140 tons per hour, its capacity being then limited by the capacity of the conveyors which were working at utmost capacity and could not handle a higher rate. The ultimate capacity of the system is at present unknown. With nor-

mal comparatively leisurely speeds of operation its capacity is ten times that of any previous system, comparison being made on a basis of separating surface areas.

5. Coal may be prepared by this process with any degree of ash content the operator desires, something which no previous process has ever accomplished. Heretofore systems of coal cleaning had made a rough division between coal and slate 10 but the percentage of coal in the slate and the percentage of slate in the coal varied from minute to minute. The idea of producing coal of standard ash content was a desideratum without a means of obtaining it. 85% efficiency has been 15 considered good for coal cleaning processes and many of the mountainous waste banks found in the coal regions contain 15% to 35% of usable fuel. By our invention these waste piles may be profitably reclaimed. No previous method was 20 capable of economically extracting the coal from such waste piles.

As many apparently widely different embodiments of this invention may be made without departing from the spirit and scope thereof, it 25 is to be understood that we do not limit ourselves to the specific embodiments thereof except as defined in the appended claims.

We claim:

1. In a mineral separation process performed 30 generally out of contact with the atmosphere, the steps of separating mixed mineral-containing materials of different specific gravities by immersing them in a parting liquid of intermediate specific gravity comprising a halogenated 35 hydrocarbon, removing the separated constituents from the parting liquid, scrubbing the separated constituents with an aqueous scrubbing liquid, removing the scrubbed materials from the process, agglomerating suspended solids and heavy liquids 40 in the used scrubbing liquid, dividing the used scrubbing liquid into watery and heavier portions, settling heavy constituents out of the said watery portion, returning the water from the settling step to the said scrubbing step for reuse, combining the sludge from the parting step with the 45 said heavier portions and said heavy constituents, dividing the relatively clean heavy liquid from the said combination of sludge and heavy fractions for reuse in the parting step of the said 50 process, and distilling the parting liquids out of the residue.

2. In a mineral separation process performed generally out of contact with the atmosphere, the steps of separating mixed mineral-containing 55 materials of different specific gravities by immersing them in a parting liquid of intermediate specific gravity comprising a halogenated hydrocarbon, scrubbing the separated constituents with an aqueous scrubbing liquid, removing the 60 scrubbed materials from the process, dividing the used scrubbing liquid into watery and heavier portions, settling heavy constituents out of the said watery portion, returning the water from the settling step to the said scrubbing step for reuse, combining the said heavier portions and 65 said heavy constituents, settling the sludge out of the said combination, dividing the said combination into sludge and liquid, and distilling the parting liquids out of the sludge.

70 3. In a mineral separation process performed generally out of contact with the atmosphere, the steps of separating mixed mineral-containing materials of different specific gravities by immersing them in a parting liquid of intermediate 75 specific gravity comprising an organic liquid,

scrubbing the separated constituents with an aqueous scrubbing liquid substantially insoluble in the parting liquid, removing the scrubbed materials from the process, dividing the used scrubbing liquid into watery and heavier portions, settling heavy constituents out of the said watery portion, combining the said heavier portions and said heavy constituents, settling the sludge out of said combination and dividing the liquids therefrom, and distilling the parting liquids out 10 of the sludge.

4. In a mineral separation process performed generally out of contact with the atmosphere, the steps of separating mixed mineral-containing materials of different specific gravities by immersing them in a parting liquid of intermediate specific gravity; scrubbing the separated constituents with an aqueous scrubbing liquid substantially insoluble in the parting liquid; separating the parting liquid and sludge from the used scrubbing liquid by settling and decantation; returning the cleansed scrubbing liquid to the scrubbing step for reuse; and recovering parting liquid from the separated parting liquid and sludge by sludge distillation.

5. In a mineral separation process performed generally out of contact with the atmosphere, the steps of separating mixed mineral-containing materials of different specific gravities by immersing them in a parting liquid of intermediate specific gravity comprising an organic liquid, scrubbing the separated constituents with an aqueous scrubbing liquid substantially insoluble in the parting liquid, removing the scrubbed materials from the process, removing the solids and heavy liquid from the used scrubbing liquid by an agglomeration and at least two settling, and removing the heavy liquid from the sludge by settling and by distillation of the sludge.

6. In a mineral separation process performed generally out of contact with the atmosphere, the steps of separating mixed mineral-containing materials of different specific gravities by immersing them in a parting liquid of intermediate specific gravity comprising an organic liquid; scrubbing the separated constituents with an aqueous scrubbing liquid substantially insoluble in the parting liquid; preparing the scrubbing liquid for reuse by agglomerating the solids and parting liquid, separating the watery from the agglomerate portion by decantation, settling additional suspended matter out of the watery portion, separating the settled matter from the relatively clean scrubbing liquid, and returning the scrubbing liquid to the scrubbing step.

7. In a mineral separation process performed generally out of contact with the atmosphere, the steps of separating mixed mineral-containing materials of different specific gravities by immersing them in a parting liquid of intermediate specific gravity comprising an organic liquid; scrubbing the separated constituents with an aqueous scrubbing liquid substantially insoluble in the parting liquid; removing the scrubbed materials from the process; and recovering the parting liquid for reuse by settling it out of, and dividing it from, the aqueous scrubbing liquid; and dividing it from admixed solids by settling, decantation of the liquid, and distillation of the solids.

8. Apparatus for the processing of minerals, being generally hermetically sealed, which comprises means to admit to the apparatus the minerals which are to be processed and means to withdraw processed materials from the appa- 75

- 5 ratus; means to separate the mineral from accompanying impurities by flotation in a liquid of intermediate specific gravity; means to scrub the so-separated materials with a liquid; means to transport the materials from the separating to the said scrubbing means; means to clean the liquid used for scrubbing the said materials comprising an agglomerator which operates upon the said used liquid and a series of at least two settling tanks which operate to retain agglomerated and settled materials, means to transport the liquid from tank to tank, and means to return the cleaned scrubbing liquid to the scrubbing means for reuse; means to recover used parting liquid from the process which comprises a sludge settling means, means to transport the materials in the bottoms of the said separating means and the said series of settling tanks to the said sludge settling means, means to withdraw clarified liquid 10 from the said settling means, a still, means to transport the settlings from the said settling means to the said still; means to receive the distillate from the said still, and means to remove the solids from the still after the distillation.
- 15 9. Apparatus for the separation of minerals from materials of different specific gravity being in general hermetically sealed, which comprises means for treating the mineral, involving in series means for separating the mineral from its impurities in a liquid of intermediate specific gravity, and means for removing the said liquid of intermediate specific gravity from the surface of the so-separated materials by washing with water; means to clean the washing water comprising 20 in series an agglomerator, and two settling tanks,
- 25 10. Apparatus for the separation of minerals from materials of different specific gravity being in general hermetically sealed, which comprises means for treating the mineral, involving in series means for separating the mineral from its impurities in a liquid of intermediate specific gravity, and means for removing the said liquid of intermediate specific gravity from the surface of the so-separated materials by washing with water; and means to clean the washing water comprising in series at least two settling tanks; means to flow the washing water from tank to tank and to return the cleaned water to the washing means for reuse; and means to recover the 25 parting liquid from the said means for cleaning the washing water which comprises in series a settling tank to receive the materials removed from the said washing water, and a still to remove heavy liquid from the matter which was 30 settled out of the heavy liquid in the said settling tank.

CERTIFICATE OF CORRECTION.

Patent No. 2,150,899.

March 21, 1939.

HENRY L. ALEXANDER, ET AL.

It is hereby certified that error appears in the printed specification of the above numbered patent requiring correction as follows: Page 1, second column, line 35, for "outweight" read outweigh; page 5, second column, line 61, for "large" read larger; page 7, second column, line 30, for "constiuents" read constituents; line 41, for "elesewhere" read elsewhere; page 13, second column, line 61, for "advantages" read advantage; and that the said Letters Patent should be read with this correction therein that the same may conform to the record of the case in the Patent Office.

Signed and sealed this 6th day of June, A. D. 1939.

Henry Van Arsdale
